(57) **CLAIM**

The ornamental design for a ceramic valve as shown and described.

DESCRIPTION

FIG. 1 is an upper perspective view of a ceramic valve showing my new design;

FIG. 2 is a front view thereof;

FIG. 3 is a rear view thereof;

FIG. 4 is a side view thereof;

FIG. 5 is an opposite side view thereof;

FIG. 6 is a top plan view thereof;

FIG. 7 is a bottom plan view thereof;

FIG. 8 is a lower perspective view thereof;

FIG. 9 is an exploded view thereof; and,

FIG. 10 is a perspective view showing the ceramic valve in a condition of use, wherein a housing is shown being positioned over the ceramic valve.

The broken line showing of the housing in the upper portion of FIG. 10 illustrates the environment of the claimed design and forms no part of the claimed design. The remaining broken lines in FIGS. 1-10 illustrate portions of the ceramic valve that form no part of the claimed design.
